UNITED STATES PATENT OFFICE

MAX DWORK, OF BROOKLYN, NEW YORK

JACK

Application filed February 27, 1930. Serial No. 431,875.

My invention relates to lifting jacks and an object of the same is to provide a lifting jack which may be engaged with any projecting part of an automobile such as the 5 chassis side bar and thereby obviates the necessity of kneeling beneath the automobile to place the jack beneath the spring or axle.

Another object of the invention is to provide a jack standard extension which may 10 be removably mounted on the lifting standard of any conventional jack.

Still another object of the invention is to provide a vertically adjustable jack standard extension having a lifting element for 15 engagement with one of the shackle bolts and which may be mounted on the extension at any selected height so that the device can be utilized on any automobile regardless of the 20 height of the chassis frame with relation to the ground.

With the preceding and other objects and advantages in mind, the invention consists in the novel combination of elements, constructions and arrangements of parts and 25 operations to be hereinafter more fully described, claimed and illustrated in the accompanying drawing, wherein:

Figure 1 is a front elevation of the invention;

Fig. 2 is a view partly in side elevation and partly in vertical section;

Fig. 3 is a horizontal section taken on line 3—3 of Fig. 2;

Fig. 4 is an elevation of the device in operative position;

Fig. 5 is a perspective of the lifting element embodied in the invention;

Fig. 6 is a view partly in section and partly in elevation of a modification of the invention; and

Fig. 7 is a perspective of the lifting element embodied in the construction disclosed in Fig. 6.

Referring to the invention in detail a conventional jack 5 whose lifting standard 6 is formed with a rectangular head or plate 7 is provided.

A jack standard extension is provided for cooperation with the lifting standard 6 comprising a vertically extending bar 8 having

a longitudinal groove 9 in its inner face and which extends the entire length of the bar.

A vertically adjustable shank 10^a is in the groove 9 and is formed with bevelled ribs 10 on one pair of its opposite faces and which are 55 slidably fitted in V-shaped grooves 11 in the parallel walls of the groove 9.

For the purpose of holding the shank 10^a at predetermined points of adjustment this shank and the bar 8 are provided with longitudinally aligned registering transverse openings 12 and 13. When the shank 10^a has been raised to a predetermined height a screw 60 or other suitable fastening 14 is engaged with the registering openings 12 and 13. 65

A lifting element is provided consisting of a cross sectionally rectangular shank 15 formed with a depending ear 16. A forwardly extending hook element 17 is formed with one side of the ear 16 which hook element is 70 adapted to engage beneath the upper shackle bolt of the automobile as shown in Fig. 4. As illustrated in Fig. 5 the upper face of the hook element 17 is recessed as indicated at 18. Normally received in the recess is an ornamental plate 19, one end of which is secured to the hook element by a suitable fastening 20. The ornamental plate 19 is for the purpose of 75 adding to the appearance of the device when it is on sale in that it cooperates with the other parts of the lifting element in giving the latter the appearance of an elephant's head. In use the shank 15 is received in any one of a plurality of rectangular transverse openings 21 with the hook element projecting forward- 80 ly from the shank 10. A set of rectangular transverse openings 22 are formed in the bar 8 for the reception of the shank 15 when the lifting element is to be located below the upper end of the bar 8. 85

For the purpose of preventing the load from accidentally slipping from the lifting element a flexible element 23 is carried by the ear 16 and is adapted to be passed around the shackle bolt as disclosed in Fig. 4. The free end of this flexible element carries a fastening 23^a adapted to be received in an opening 24^a in the ear 16. In order to hold the lifting element against accidental longitudinal movement the rear end of the shank 15 is 90 95 100

formed with a transverse opening 25 which receives a cotter pin 26.

For the purpose of mounting the jack standard extension on the lifting standard 6 the lower end of the bar 8 is formed with a horizontal plate 27 which is adapted to rest on the lifting head 7. Parallel side flanges 28 depend from opposite sides of the plate 27 while a rear flange 29 depends from the rear edge of the plate 27. Two opposite edges of the lifting head 7 are held between the flange 29 and a U-shaped fastening 30 which as shown in Figs. 1 and 2 extends through openings 31 in the plate 27 and projects below the lifting head 7. The U-shaped fastening 30 is carried on a chain 32 which has one end anchored to an eye 33 attached to the lower end of the shank 10^a. Oppositely extending set screws 34 are threadedly engaged with the flanges 28 and engage opposite sides of the standard 6. It will be thus seen that the set screws 34, removable fastening 30 and flange 29 cooperate to rigidly and removably hold the jack extension on the lifting standard of the jack.

Dirt or other foreign matter may lodge between the shank 10 and walls of the groove 9 and prevent free movement of the shank. To overcome this condition an expansible coil spring 35 is interposed between the lower end of the shank 10^a and the upper face of the plate 27. It will be seen that upon tapping upon the upper end of the shank 10^a the spring 35 will be compressed whereupon it will expand and jar the shank 10^a and free the same. In the modification disclosed in Figs. 6 and 7 the shank 15 is omitted and in lieu thereof the lifting element is formed with a rectangular socket 36 which snugly fits upon the upper end of the shank 10^a.

In the operation of both forms of the invention the device is placed in alignment with the rear end of one of the chassis side bars and the hook element engaged beneath the upper end spring shackle bolt as shown in Fig. 4. The jack 5 is then operated in the usual manner to lift one side of the automobile. While the lifting element is preferably adapted to be engaged with the upper shackle bolt as above stated, it may be engaged with any suitable projecting part of the automobile.

I claim:

1. A lifting jack extension comprising a vertically extending member provided with a lifting element, a plate carried by the lower end of the vertically extending member adapted to rest upon a jack standard, parallel flanges depending from the plate, a third flange depending from the plate at right angles to the first mentioned flanges and contacting one side of said jack standard, oppositely extending threaded elements carried by the parallel flanges and engageable with the jack standard to hold the plate against

movement in two directions, and a removable fastening passing through the plate and contacting the side of said jack standard opposite said other flange and serving therewith to hold the plate against movement in two other directions.

2. A lifting jack extension comprising telescopically arranged members having two sets of cross sectionally dissimilar holes, means of a cross section to suit one of the sets, being insertible in a pair of holes of said one set thus securing the members and holding all holes of the other set in registration, and a lifting element cooperating with said jack extension, said element having a shank of a cross section suiting the other set of holes, said shank fitting a selected pair of holes of said other set.

MAX DWORK.
